UNITED STATES PATENT OFFICE.

GUSTAV B. PETSCHÉ, OF YONKERS, NEW YORK.

ROTARY PUMP OR COMPRESSOR.

1,384,276.

Specification of Letters Patent. Patented July 12, 1921.

Application filed November 2, 1920. Serial No. 421,272.

To all whom it may concern:

Be it known that I, GUSTAV B. PETSCHÉ, a citizen of the United States of America, and resident of Yonkers, in the county of 5 Westchester, in the State of New York, have invented a certain new and useful Improvement in Rotary Pumps or Compressors, of which the following is a true and exact description, reference being had to the accompanying drawings, which form a part thereof.

My invention relates to rotary pumps of the kind provided with a rotary eccentric ring piston having an extension which serves 15 as a partition between the admission and discharge ports of the pump and the object of my improvements is to design a pump of this kind which will be especially suitable for use as a dry air pump to evacuate air from condensers, especially such condensers as are used in connection with steam turbines in which the vacuum created is very great, corresponding for instance to an absolute pressure of a half-inch mercury column. As the 20 air has to be compressed and discharged into the atmosphere, the pressure of which corresponds to a thirty inch mercury column, the ratio of the two pressures are as one to sixty. In practice it has been found that in 25 pumps or compressors used for this class of work the final temperature which is a natural function of the pressure ratio is so high, that the lubrication used in the compressor often carbonizes, with the natural injury to 30 the wearing surfaces of the pump. Obviously the disadvantages noted can be overcome by somewhat raising the initial pressure on the admission side of the pump without affecting the pressure in the condensers 35 for instance, an increase in the pressure on the admission side of the pump of only one half inch of mercury would reduce the ratio of pressure to from one to thirty and the temperature due to compression accordingly. In my construction I provide for the 40 closing of the admission port after the cylinder has received its full charge of air and for the subsequent increase of pressure in the air to be compressed, by making use of 45 the back flow of compressed air from the clearance spaces of the pump and from the receiving chamber through the discharge valves before these are seated. This will 50 raise the initial pressure to a point which 55 will no longer result in the creation of an injurious temperature in the pump cylinder

at the end of compression of the air, and my invention has particularly to do with the provision of a simple valve structure opening under the pressure of the fluid in the 60 compressor and closing at the end of the compression stroke by a partial back flow of fluid in the receiver. Such a valve will permit sufficient back flow before closing as will raise the pressure of the air about to be 65 compressed to such a point as will avoid the creation of a too high temperature.

The nature of my invention will be best understood as described in connection with the drawings in which I have illustrated my 70 invention as applied to a form of compressor and a general construction especially well adapted for its most advantageous use in which—

Figure 1 is a side elevation from the one 75 side of a twin cylinder compressor taken on the sectional line 1—1 of Fig. 2.

Fig. 2 is a side elevation of the compressor shown partly in section on the line 2—2 of Fig. 1.

Fig. 3 is an enlarged sectional view of the valve construction, and

Fig. 4 a face view of this valve construction.

A and A' indicate two compressor cylinders formed in the same casting and closed by face plates A² and A³. B indicates the periphery of the compressor cylinder interrupted at B' and B² to give clearance to the piston extension. C is a segmental cylindrical bearing surface formed in a cylinder casing. D is the admission chamber of the compressor having an admission port D' which, as shown, enters the admission side of the pump through an opening in the 95 cylindrical bearing C. E is the delivery chamber of the pump having, as shown, an opening closed by a face plate M. F is the wall surface of the pump extending from the point B² of the cylinder to one side of 100 the bearing surface C, the form in this wall must be such as to give clearance to the piston extension, to be described, which is shown in Fig. 1 in the position of closest approach to this wall. A portion of this wall 105 F is practically straight and through this wall I form delivery ports indicated at E' which are preferably in ring form, as shown, and open into the delivery chamber E. G is the driving shaft of the compressor 110 having secured to its eccentrics G' on which are the eccentric ring pistons H formed

with extensions H' which form partitions between the admission and delivery ports and, as shown, are hinged to one side of an oscillatory member I' which fits and moves 5 on the bearing surface C and oscillates on a bearing I . The piston H' is hinged to this oscillatory member at I^3 and, as shown, preferably the oscillatory member comprises a valve I^2 so located that it closes the port 10 D' after the pump cylinder has been fully charged and before the piston leaves contact with the periphery of its cylinder at B^2 remaining closed until the piston has resumed contact with the periphery of its cylinder at B' . As shown, the oscillatory member has a clearance provided between the portion I' and the valve I^2 and a port C' is formed through the wall C extending 15 into the admission chamber D .

20 J in Fig. 3 indicates the valve for closing the delivery ports E' . It is made in the form of an annular ring with a peripheral flange J' and is held in place and prevented from moving too far from its seat by an elastic abutment plate K secured in place by a bolt L and preferably formed in a series of 25 tongues or wings by having formed in its periphery K' openings through its edges as indicated at K^2 .

30 In operation the air from the compressor passes through the chamber D and the port D' until the pump chamber is fully charged which occurs immediately before the parts reach the position shown in Fig. 1 at which 35 point the piston G is about to leave contact with the point B^2 on the cylinder periphery and valve I^2 closes the admission port. A further movement of the piston permits back flow of the air from the clearance 40 spaces and also from the receiver E , the air flowing backward causing the valves J' to close the ports E' after a small amount of compressed air has passed back into the cylinder. The back flow of the compressed 45 air from the receiver and the clearance spaces will be such as to raise the pressure of the air in the compressor to such a point as may be desired.

During the compression stroke of the piston 50 ton which begins when the piston comes in contact with the periphery of the cylinder at B' the air is compressed until this pressure equals that in the receiver E after which the valves J open freely permitting 55 the escape of the air into the receiver.

The special construction of the valves J with the peripheral flanges J' is such as to greatly strengthen these valves and prevent the occurrence of such breakage perforations as has been found liable to occur with the use of thin unflanged plates. The flange J' also serves in connection with the flexible abutment K to center and hold the valve in proper position.

While my invention has been especially 65 designed and is especially adapted for such uses as have been indicated it is obviously capable of other useful employment and while the special construction of the pump indicated is, I believe, exceedingly meritorious 70 it is obvious that my invention can also be applied to modified forms of rotary piston pumps.

Having now described my invention, what I claim as new and desire to secure by Letters Patent, is:

1. In combination with a rotary pump having a rotary eccentric ring piston and a piston extension forming a partition between the admission and exhaust ports, a 80 valve for closing the admission port, means for moving said valve whereby it closes said port during the period when the piston is out of contact with its cylinder and leaves the port open at all other times and 85 a valve for closing the delivery port opening under the pressure of the fluid in the pump and closing with the back flow when said pressure ceases.

2. In combination with a rotary pump 90 having a rotary eccentric ring piston, a piston extension forming a partition between the admission and exhaust ports of the pump, an oscillatory member moving in a segmental cylindrical bearing to one side 95 of which the piston extension is hinged and a wall section extending from the periphery of the pump cylinder to one end of the segmental bearing, an admission valve having means for closing it during the period when the piston is out of contact with its cylinder, one or more delivery ports formed through 100 the wall section aforesaid and valves for closing said delivery ports opening under the pressure of the fluid in the pump and 105 closing with the back flow when said pressure ceases.

3. In combination with a rotary pump having a rotary eccentric ring piston, a piston extension forming a partition between 110 the admission and exhaust ports of the pump, an oscillatory member moving in a segmental cylindrical bearing to one side of 115 which the piston extension is hinged and a wall section extending from the periphery of the pump cylinder to one end of the segmental bearing, an admission valve moving with the oscillatory member and acting to close the admission port during the period 120 when the piston is out of contact with the periphery of its cylinder, one or more delivery ports formed through the wall section aforesaid and valves for closing said 125 delivery ports opening under the pressure of the fluid in the pump and closing with the back flow when said pressure ceases.
